UNITED STATES PATENT OFFICE.

HARRY WILSON, OF WASHINGTON, DISTRICT OF COLUMBIA, ASSIGNOR TO THE DRIGGS-SEABURY ORDNANCE CORPORATION, OF PHILADELPHIA, PENNSYLVANIA, A CORPORATION OF NEW JERSEY.

PERCUSSION-FUSE FOR SHELLS.

No. 805,251.

Specification of Letters Patent.

Patented Nov. 21, 1905.

Application filed September 21, 1904. Serial No. 225,371.

To all whom it may concern:

Be it known that I, HARRY WILSON, a citizen of the United States, residing at Washington, in the District of Columbia, have invented certain new and useful Improvements in Percussion-Fuses for Shells; and I do hereby declare the following to be a full, clear, and exact description of the invention, such as will enable others skilled in the art to which it applies to make and use the same.

My present invention relates to improvements in percussion-fuses for shells, and it is intended to provide a fuse which is simple in construction, efficient in operation, and safe against accidents.

The invention relates to that class of fuses in which the fuse is safe at all times except when the shell is spinning, but in which the parts are thrown in the operative position by the action of centrifugal force due to the spinning of the shell, occasioned by the rifling of the gun.

My invention will be understood by reference to the accompanying drawings, in which the same parts are indicated by the same letters throughout the several views.

Figure 1 is a central longitudinal section through the shell along the line 1 1 of Fig. 2, parts being shown in elevation. Fig. 2 is a section along the line 2 3 of Fig. 1 and shows the segments in the closed or the locked position. Fig. 3 is a similar section to Fig. 2 and shows the locking-segments in the open or unlocked position, which position would be assumed when the shell was spinning. Fig. 4 shows a section along the line 4 4 of Fig. 1 and looking in the direction of the arrows, and Fig. 5 is a detail showing the front face of the plunger.

A represents the fuse-stock, which is screw-threaded, as at a , is bored out as at A^0 , preferably in the form of a cylinder, with a cylindrical lug A' at the bottom of the bore. The forward portion of the bore of the fuse-stock is screw-threaded, as at a^0 , to receive the plug C, and is enlarged in diameter, as at a' , to form a powder-chamber for the ignition charge, and is provided with lips a^2 to hold the disk M in front of the powder L.

B represents the plunger, which is provided on its front face with two sockets b b' , into one of which sockets projects the firing point or pin b^2 . This plunger B is held against

turning in the fuse-stock in any suitable way, as by means of a pin a^4 , projecting into a longitudinal groove b^4 , as shown in Fig. 1.

The plug C has secured thereto a pin D, on which is pivoted the arm e, carrying the block E, in which is mounted the primer e'.

Passing through the pin D is the bent spring d, which spring bears against the block E, tending to throw the block from the position indicated in full lines to that indicated in dotted lines in Fig. 4. The block E normally projects into the socket b in the front face of the plunger when the parts are in the locked position; but when the plunger B moves backward, as will be hereinafter described, the block E is released from the socket b and is thrown, by means of the spring d, to the position shown in dotted lines in Fig. 4. At this time the primer will be in the path of the firing-pin b^2 , and the opening e^0 in the block E will register with the opening e^0 in the plug C, which opening e^0 is normally closed by a piece of paper or tin-foil c'. At this time the fuse will be "armed."

Between the plunger and the plug C the coil-spring F is mounted under compression. This spring need not be of any great strength, but should have sufficient force to move the plunger and other parts rearward when the plunger is unlocked, as will be hereinafter described.

In rear of the plunger B, I provide two blocks H H' in the form of segments of a cylinder, which blocks are recessed, as at h^0 , to receive the springs I', mounted on the shank I of a bolt having heads i i' of slightly-less diameter than the recesses h^0 . One of these heads, as at i , may be made detachable and the other fixed, or both may be made detachable, as may be desired. These blocks H H' are also recessed, as at h , to fit over the cylindrical lug A' when the segments are in the closed position, as shown in Fig. 1, and are also recessed, as at h' , to pass rearward over the cylindrical lug A' when the segments are in the open position, as shown in Fig. 3. These segments and the bolt I are mounted in a sleeve K, which is loosely assembled in the fuse-stock A.

The operation of the device is as follows: The parts would normally be in the position shown in Figs. 1 and 2; but when the gun is fired the shell will be spun up by the rifling,

- which will cause the segments H H' to be thrown outward by centrifugal force against the action of the springs I' until these segments reach the position shown in Fig. 3. 5 This will cause the cut-away portions $\bar{h}'$ of these segments to clear the outer edge of the cylindrical lug A', and the plunger B and the sleeve K, with the parts contained therein, will slide backward, due to inertia, and supplemented by the positive action of the coil-spring F until arrested by the rear face a^o of the chamber A^o in the fuse-stock. As the plunger recedes it will release the block E, causing the spring d to throw the block over 10 to the position indicated in dotted lines in Fig. 4, as hereinbefore described, and on striking the target the plunger will fly forward, exploding the primer and setting fire to the ignition charge. 15
- 20 It will be seen that the fuse cannot be fired by any accident until the shell is spinning rapidly and that the two segments H H' serve as a double lock to keep the plunger in the forward position, while the primer cannot be 25 fired until the plunger has been forced rearward, which can only take place when the shell is spinning. It will also be noted that on striking the target not only will the whole weight of the plunger be thrown against the 30 primer, but the weight of the sleeve K and the segments H H' will supplement the weight of the plunger and all these parts will serve as a hammer in exploding the primer.
- The purpose of the sleeve K is not only for 35 convenience in assembling the parts, but also to permit the segments H H' to be moved backward in the fuse-stock without requiring too much force. The outer surface of the sleeve slides freely in the fuse-stock, and when 40 the shell is spinning rapidly the movable segments H H' are held with considerable force against the inner surface of the sleeve K, but do not materially affect the friction between the sleeve K and the fuse-stock, whereas if 45 these segments H H' engaged directly with the inner surface of the fuse-stock excessive friction would be set up, preventing the movement to the rear of the segments and of the plunger.
- 50 Various changes in the construction, combination, and arrangement of parts might be made which could be used without departing from the spirit of my invention.
- Having thus described my invention, what 55 I claim, and desire to secure by Letters Patent of the United States, is—
1. In a fuse, the combination with a plunger, provided with an eccentric firing-pin, a block carrying the primer normally engaging 60 the front of said plunger eccentric to said firing-pin, means for normally holding the plunger in engagement with said block, and for releasing the plunger, controlled by the spinning of the shell, means for moving the 65 plunger to the rear when released, and means

for moving the primer in front of the firing-pin when the plunger is moved rearward, substantially as described.

2. In a fuse, the combination with a plunger, provided with an eccentric firing-pin, a block carrying the primer normally engaging the front of said plunger eccentric to said firing-pin, means for normally holding the plunger in engagement with said block, and for releasing the plunger, controlled by the 70 spinning of the shell, means for moving the plunger to the rear when released, and a spring engaging the block carrying the primer and adapted to throw the primer in front of the firing-pin when the plunger is moved to 75 the rear, substantially as described.

3. In a fuse, the combination with a plunger, provided with an eccentric firing-pin, a plug secured in the fuse-stock and perforated in front of said firing-pin, a block carrying 85 the primer pivoted to said plug, and normally engaging the front of said plunger eccentric to said firing-pin, means for normally holding the plunger in engagement with said block, and for releasing the plunger, controlled by 90 the spinning of the shell, means for moving the plunger to the rear when released, and means for moving the primer in front of the firing-pin when the plunger is moved rearward, substantially as described.

4. In a fuse, the combination with a plunger, provided with an eccentric firing-pin, a plug secured in the fuse-stock and perforated in front of said firing-pin, a block carrying 95 the primer pivoted to said plug, and normally engaging the front of said plunger eccentric to said firing-pin, means for normally holding the plunger in engagement with said block, and for releasing the plunger, controlled by 100 the spinning of the shell, means for moving the plunger to the rear when released, and a spring connected to the primer-block for moving the primer in front of the firing-pin when the plunger is moved rearward, substantially as described.

5. In a fuse, the combination with a plunger, provided with an eccentric firing-pin, a plug secured in the fuse-stock and perforated in front of said firing-pin, a block carrying 115 the primer pivoted to said plug, and normally engaging the front of said plunger eccentric to said firing-pin, means for normally holding the plunger in engagement with said block, and for releasing the plunger, controlled by 120 the spinning of the shell, means for moving the plunger to the rear when released, and a spring engaging the block carrying the primer and adapted to throw the primer in front of the firing-pin when the plunger is moved to 125 the rear, substantially as described.

6. In a fuse, the combination with a plunger, provided with an eccentric firing-pin, a block carrying the primer normally engaging the front of said plunger eccentric to said firing-pin, spring-compressed segments nor- 130

5 mally holding the plunger in engagement with said block, but releasing said plunger when thrown outward by centrifugal force, means for moving the plunger to the rear when released, and means for moving the primer in front of the firing-pin when the plunger is moved rearward, substantially as described.

7. In a fuse, the combination with a plunger, provided with an eccentric firing-pin, a 10 block carrying the primer normally engaging the front of said plunger eccentric to said firing-pin, spring - compressed segments normally holding the plunger in engagement with said block, but releasing said plunger when 15 thrown outward by centrifugal force, means for moving the plunger to the rear when released, and a spring engaging the block carrying the primer and adapted to throw the primer in front of the firing-pin when the plunger is moved to the rear, substantially as described.

8. In a fuse, the combination with a plunger, provided with an eccentric firing-pin, a block carrying the primer normally engaging 25 the front of said plunger eccentric to said firing-pin, means for normally holding the plunger in engagement with said block, and for releasing the plunger, controlled by the spinning of the shell, a coil-spring mounted in 30 front of said plunger and moving same to the rear when released, and means for moving the primer in front of the firing-pin when the plunger is moved rearward, substantially as described.

35 9. In a fuse, the combination with a plunger, provided with an eccentric firing-pin, a block carrying the primer normally engaging the front of said plunger eccentric to said firing-pin, means for normally holding the plunger in engagement with said block, and for releasing the plunger, controlled by the spinning of the shell, a coil-spring mounted in 40 front of said plunger and moving same to the rear when released, and a spring engaging the block carrying the primer and adapted to throw the primer in front of the firing-pin when the plunger is moved to the rear, substantially as described.

45 10. In a fuse, the combination with a plunger, provided with a firing-pin, a block carrying the primer normally engaging the front of said plunger eccentric to said firing-pin, means for normally holding the plunger forward in engagement with said block, and for 50 releasing the plunger, controlled by the spinning of the shell, means for moving the plunger to the rear when released, and means for moving the primer in front of the firing-pin when the plunger is moved forward, substantially as described.

60 11. In a fuse, the combination with a plunger, provided with two recesses in its front face, and a firing-pin projecting into one of said recesses, a block carrying the primer normally 65 engaging in the second recess in the

front of said plunger eccentric to said firing-pin, means for normally holding the plunger forward in engagement with said block, and for releasing the plunger, controlled by the spinning of the shell, means for moving the plunger to the rear when released, and a spring engaging the block carrying the primer and adapted to throw the primer in front of the firing-pin when the plunger is moved to the rear, substantially as described.

70 12. In a fuse, the combination with a plunger, provided with two recesses in its front face, and a firing-pin projecting into one of said recesses, a plug secured in the fuse-stock and perforated in front of said firing-pin, a 80 block carrying the primer pivoted to said plug, and normally engaging the second recess in the front of said plunger eccentric to said firing-pin, means for normally holding the plunger forward in engagement with said block, and for releasing the plunger, controlled by the spinning of the shell, means for moving the plunger to the rear when released, and means for moving the primer in front of the firing-pin when the plunger is moved rearward, substantially as described.

75 13. In a fuse, the combination with a plunger, provided with two recesses in its front face, and a firing-pin projecting into one of said recesses, a plug secured in the fuse-stock 90 and perforated in front of said firing-pin, a block carrying the primer pivoted to said plug, and normally engaging in the second recess in the front of said plunger eccentric to said firing-pin, means for normally holding the plunger forward in engagement with said block, and for releasing the plunger, controlled by the spinning of the shell, means for moving the plunger to the rear when released, and a spring connecting to the primer-block for 95 moving the primer in front of the firing-pin when the plunger is moved rearward, substantially as described.

100 14. In a fuse, the combination with a plunger, provided with two recesses in its front face, and a firing-pin projecting into one of said recesses, a plug secured in the fuse-stock 105 and perforated in front of said firing-pin, a block carrying the primer pivoted to said plug, and normally engaging in the second recess in the front of said plunger eccentric to said firing-pin, means for normally holding the plunger forward in engagement with said block, and for releasing the plunger, controlled by the spinning of the shell, means for moving the plunger to the rear when released, and a spring engaging the block carrying the primer and adapted to throw the primer in front of the firing-pin when the plunger is moved to the rear, substantially as described.

110 15. In a fuse, the combination with a plunger provided with a firing-pin and a recess eccentric to said pin, of a block carrying the primer normally engaging in said recess, means for normally holding the plunger for 115

ward in engagement with said block, and for releasing the plunger, controlled by the spinning of the shell, a coil-spring mounted in front of said plunger and moving same to the rear when released, and means for moving the primer in front of the firing-pin when the plunger is moved rearward, substantially as described.

16. In a fuse, the combination with a plunger, provided with a firing-pin and a recess eccentric to said pin, of a block carrying the primer normally engaging in said recess, means for normally holding the plunger forward in engagement with said block, and for releasing the plunger, controlled by the spinning of the shell, a coil-spring mounted in front of said plunger and moving same to the rear when released, and a spring engaging the block carrying the primer and adapted to throw the primer in front of the firing-pin when the plunger is moved to the rear, substantially as described.

17. In a fuse, the combination with a plunger, provided with a firing-pin and a recess eccentric to said pin, of a block carrying the primer normally engaging in said recess, means for normally holding the plunger forward in engagement with said block, and for releasing the plunger, controlled by the spinning of the shell, means for moving the plunger to the rear when released, and means for moving the primer in front of the firing-pin when the plunger is moved rearward, substantially as described.

18. In a fuse, the combination with a plunger, provided with a firing-pin and a recess eccentric to said pin, of a block carrying the primer normally engaging in said recess, means for normally holding the plunger forward in engagement with said block, and for releasing the plunger, controlled by the spinning of the shell, means for moving the plunger to the rear when released, and a spring engaging the block carrying the primer and adapted to throw the primer in front of the firing-pin when the plunger is moved to the rear, substantially as described.

19. In a fuse, the combination with a plunger, provided with a firing-pin and a recess eccentric to said pin, of a plug secured in the fuse-stock and perforated in front of said firing-pin, a block carrying the primer pivoted to said plug, and normally engaging in said recess, means for normally holding the plunger forward in engagement with said block, and for releasing the plunger, controlled by the spinning of the shell, means for moving the plunger to the rear when released, and means for moving the primer in front of the firing-pin when the plunger is moved rearward, substantially as described.

20. In a fuse, the combination with a plunger, provided with a firing-pin and a recess eccentric thereto, of a block carrying the primer normally engaging in said recess, spring-com-

pressed segments normally holding the plunger forward in engagement with said block, but releasing said plunger when thrown outward by centrifugal force, means for moving the plunger to the rear when released, and a 70 spring engaging the block carrying the primer, and adapted to throw the primer in front of the firing-pin when the plunger is moved to the rear, substantially as described.

21. In a fuse, the combination with a plunger, provided with a firing-pin and a recess eccentric thereto, of a block carrying the primer normally engaging in said recess, spring-compressed segments normally holding the plunger in engagement with said block, but releasing said plunger when thrown outward by centrifugal force, means for moving the plunger to the rear when released, and means for moving the primer in front of the firing-pin when the plunger is moved rearward, substantially as described.

22. In a fuse, the combination with a plunger, provided with a firing-pin and a recess eccentric thereto, of a block carrying the primer normally engaging in said recess, 90 spring-compressed segments normally holding the plunger in engagement with said block, but releasing said plunger when thrown outward by centrifugal force, a coil-spring under compression mounted in front of said 95 plunger for moving the plunger to the rear when released, and means for moving the primer in front of the firing-pin when the plunger is moved rearward, substantially as described.

23. In a fuse, the combination with a plunger, provided with a firing-pin, a block carrying the primer normally held eccentric to said firing-pin, spring-compressed segments normally holding the plunger forward in engagement with said block, but releasing said plunger when thrown outward by centrifugal force, means for moving the plunger to the rear when released, and means for moving the primer in front of the firing-pin when the plunger is moved rearward, substantially as described.

24. In a fuse, the combination with a plunger, provided with a firing-pin, a block carrying the primer normally held eccentric to said firing-pin, spring-compressed segments normally holding the plunger forward in engagement with said block, but releasing said plunger when thrown outward by centrifugal force, a coil-spring under compression mounted in front of said plunger for moving the plunger to the rear when released, and means for moving the primer in front of the firing-pin when the plunger is moved rearward, substantially as described.

25. In a fuse, the combination with a plunger, provided with a firing-pin, a block carrying the primer normally held eccentric to said firing-pin, spring-compressed segments normally holding the plunger forward in engage- 130

ment with said block, but releasing said plunger when thrown outward by centrifugal force, means for moving the plunger to the rear when released, and a spring engaging the block carrying the primer and adapted to throw the primer in front of the firing-pin when the plunger is moved to the rear, substantially as described.

26. In a fuse, the combination with a plunger, provided with a firing-pin, a block carrying the primer normally held eccentric to said firing-pin, spring-compressed segments normally holding the plunger forward in engagement with said block, but releasing said plunger when thrown outward by centrifugal force, a coil-spring under compression mounted in front of said plunger for moving the plunger to the rear when released, and a spring engaging the block carrying the primer and adapted to throw the primer in front of the firing-pin when the plunger is moved to the rear, substantially as described.

27. In a fuse, the combination with a fuse-stock having a boss or lug projecting inwardly from the base thereof, of a plunger, provided with a firing-pin and a recess eccentric thereto, a block carrying the primer normally engaging in said recess, spring-compressed segments normally engaging the boss in the fuse-stock and holding the plunger forward in engagement with said block, but clearing said boss and releasing said plunger when thrown outward by centrifugal force, means for moving the plunger to the rear when released, and a spring engaging the block carrying the primer, and adapted to throw the primer in front of the firing-pin when the plunger is moved to the rear, substantially as described.

28. In a fuse, the combination with a fuse-stock having a boss or lug projecting inwardly from the base thereof, of a plunger, provided with a firing-pin and a recess eccentric thereto, a block carrying the primer normally engaging in said recess, spring-compressed segments normally engaging the boss in the fuse-stock and holding the plunger forward in engagement with said block, but clearing said boss and releasing said plunger when thrown outward by centrifugal force, means for moving the plunger to the rear when released, and means for moving the primer in front of the firing-pin when the plunger is moved rearward, substantially as described.

29. In a fuse, the combination with a fuse-stock having a boss or lug projecting inwardly from the base thereof, of a plunger, provided with a firing-pin and a recess eccentric thereto, a block carrying the primer normally engaging in said recess, spring-compressed segments normally engaging the boss in the fuse-stock and holding the plunger forward in engagement with said block, but clearing said boss and releasing said plunger when thrown outward by centrifugal force, a coil-spring under compression mounted in front of said plunger

for moving the plunger to the rear when released, and means for moving the primer in front of the firing-pin when the plunger is moved rearward, substantially as described.

30. In a fuse, the combination with a fuse-stock having a boss or lug projecting inwardly from the base thereof, of a plunger, provided with a firing-pin and a recess eccentric thereto, a block carrying the primer normally engaging in said recess, spring-compressed segments normally engaging the boss in the fuse-stock and holding the plunger forward in engagement with said block, but clearing said boss and releasing said plunger when thrown outward by centrifugal force, means for moving the plunger to the rear when released, and means for moving the primer in front of the firing-pin when the plunger is moved rearward, substantially as described.

31. In a fuse, the combination with a fuse-stock having a boss or lug projecting inwardly from the base thereof, of a plunger provided with a firing-pin, a block carrying the primer normally held eccentric to said firing-pin, spring-compressed segments normally engaging the boss or lug in the fuse-stock and holding the plunger forward in engagement with said block, but releasing said plunger when thrown outward by centrifugal force, a coil-spring under compression mounted in front of said plunger for moving the plunger to the rear when released, and means for moving the primer in front of the firing-pin when the plunger is moved rearward, substantially as described.

32. In a fuse, the combination with a fuse-stock having a boss or lug projecting inwardly from the base thereof, of a plunger provided with a firing-pin, a block carrying the primer normally held eccentric to said firing-pin, spring-compressed segments normally engaging the boss or lug in the fuse-stock and holding the plunger forward in engagement with said block, but releasing said plunger when thrown outward by centrifugal force, means for moving the plunger to the rear when released, and a spring engaging the block carrying the primer and adapted to throw the primer in front of the firing-pin when the plunger is moved to the rear, substantially as described.

33. In a fuse, the combination with a fuse-stock having a boss or lug projecting inwardly from the base thereof, of a plunger provided with a firing-pin, a block carrying the primer normally held eccentric to said firing-pin, spring-compressed segments normally engaging the boss or lug in the fuse-stock and holding the plunger forward in engagement with said block, but releasing said plunger when thrown outward by centrifugal force, a coil-spring under compression mounted in front of said plunger for moving the plunger to the rear when released, and a spring engaging the block carrying the primer and adapted to

throw the primer in front of the firing-pin when the plunger is moved to the rear, substantially as described.

34. In a fuse, the combination with a plunger, provided with an eccentric firing-pin, a block carrying a primer normally engaging said plunger eccentric to said firing-pin, means for normally holding the plunger in engagement with said block, and for releasing the plunger controlled by the spinning of the shell, means for moving the plunger longitudinally of the shell when released, and means for moving the primer in front of the firing-pin when the plunger is moved, substantially 15 as described.

35. In a fuse, the combination with a plunger, provided with an eccentric firing-pin, a block carrying the primer normally engaging said plunger eccentric to said firing-pin, means 20 for normally holding the plunger in engagement with said block, and for releasing the plunger controlled by the spinning of the shell, means for moving the plunger when released, and a spring engaging the block carrying the primer and adapted to throw the primer in front of the firing-pin when the plunger is moved, substantially as described.

36. In a fuse, the combination of a plunger, provided with an eccentric firing-pin, a plug 30 secured in the fuse-stock and perforated opposite said firing-pin, a block carrying the primer pivoted to said plug, and normally engaging said plunger eccentric to said firing-pin, means for normally holding the plunger in engagement with said block, and for releasing the plunger, controlled by the spinning of the shell, means for moving the plunger when released, and means for moving the primer in front of the firing-pin when the plunger is 35 moved, substantially as described.

37. In a fuse, the combination of a plunger, provided with an eccentric firing-pin, a plug secured in the fuse-stock and perforated opposite said firing-pin, a block carrying the 40 primer pivoted to said plug, and normally engaging said plunger eccentric to said firing-pin, means for normally holding the plunger in engagement with said block, and for releasing the plunger, controlled by the spinning of the shell, means for moving the plunger longitudinally of the shell when released, and a spring connected to the primer-block for moving the primer in front of the firing-pin when the plunger is moved, substantially 45 as described.

38. In a fuse, the combination of a plunger, provided with an eccentric firing-pin, a plug

secured in the fuse-stock and perforated opposite said firing-pin, a block carrying the primer pivoted to said plug, and normally engaging said plunger eccentric to said firing-pin, means for normally holding the plunger in engagement with said block, and for releasing the plunger controlled by the spinning of the shell, means for moving the plunger longitudinally of the shell when released, and a spring engaging the block carrying the primer and adapted to throw the primer in line with the firing-pin when the plunger is moved, substantially as described. 60

39. In a fuse, the combination with a plunger, provided with an eccentric firing-pin, a block carrying the primer normally engaging said plunger eccentric to said firing-pin, means for normally holding the plunger in engagement with said block, and for releasing the plunger, controlled by the spinning of the shell, a coil-spring for said plunger and moving the same when released, and means for alining the primer with the firing-pin when the plunger is moved, substantially as described. 75

40. In a fuse, the combination with a plunger, provided with an eccentric firing-pin, a block carrying a primer normally engaging said plunger eccentric to said firing-pin, means for normally holding the plunger in engagement with said block, and for releasing the plunger, controlled by the spinning of the shell, a coil-spring for said plunger and moving the same longitudinally of the shell when released, and a spring engaging the block carrying the primer and adapted to aline the primer with the firing-pin when the plunger is moved, substantially as described. 80

41. In a fuse, the combination with a plunger, provided with a firing-pin, a block carrying the primer normally engaging said plunger, eccentric to said firing-pin, means for normally holding the plunger in engagement with said block, and for releasing the plunger, controlled by the spinning of the shell, means for moving the plunger longitudinally of the shell when released, and means for alining the primer with the firing-pin when the plunger is moved, substantially as described. 90

In testimony whereof I affix my signature in presence of two witnesses.

HARRY WILSON.
